GOLF CLUB WITH AUXILIARY FIXTURES

Dwight W. Gibbs and Raymond R. Carter, Tucson, Ariz.,
assignors to C. G. Originals

Filed Apr. 26, 1971, Ser. No. 137,738

Term of patent 14 years

Int. Cl. D21—02

U.S. Cl. D34—5 GC

The figure is a quarter frontal perspective view of a golf club with auxiliary fixtures showing our new design.

The side of the club opposite to that illustrated in the figure is substantially the same in appearance as the side depicted in the figure.

We claim:

The ornamental design for a golf club with auxiliary
